Application July 30, 1932, Serial No. 626,832

14 Claims. (Cl. 105—414)

This invention aims to provide an improved type of underframe for use on railway cars and the like. The improved frame includes a pair of integral one-piece end castings which are secured to spaced rolled metal sections forming a center sill. The end frames include draft sill and body bolster portions which are rigidly braced to one another by integral diagonal struts. The parts are preferably so designed and arranged that the axes of the center sill and the draft sill portions of the end frames substantially or approximately coincide with the center line along which draft and buffing strains are exerted. This relationship is deemed important as it enables the utilization of the maximum strength of all fibres of the members which collectively constitute the underframe unit. The improved underframe is of simple construction which is advantageous because it provides an assembly which can readily be fabricated in most railway repair shops without the necessity of investing in expensive and otherwise useful equipment. The improved design also aims to provide a construction in which a minimum number of rivets are required, and such rivets as are used are so located that they can be machine driven. This is considered advantageous because of the uncertainty of hand driven rivets in apparatus of this character which is subjected to repeated shocks and reversing stresses.

The foregoing and various other more detailed features of the invention will be fully apparent from the following specification when read in connection with the accompanying drawings.

35 In the drawings—

Fig. 1 is a plan view of a railway car underframe illustrating a preferred embodiment of the invention;

Fig. 2 is an elevation with parts shown in section, as indicated by the staggered line 2—2 of Fig. 1;

Fig. 3 is a vertical longitudinal section through one of the end frames showing a portion of the center sill secured thereto, the view being taken 45 on line 3—3 of Fig. 1;

Fig. 4 is an enlarged plan view of one end of the underframe, parts being broken away in the interest of clearness;

Fig. 5 is a transverse section on line 5—5 of Fig. 1, parts beyond the plane of section being omitted in the interest of clearness;

Fig. 6 is a fragmentary section on line 6—6 of Fig. 1;

Fig. 7 is a transverse section on staggered line 55 7—7 of Fig. 1;

Fig. 8 is an end view of the underframe;

Fig. 9 is a detail plan of one of the end castings of the underframe having integral draft sill and body bolster portions;

Fig. 10 is a longitudinal section on line 10—10 of Fig. 9;

Fig. 11 is a detail section on line 11—11 of Fig. 9;

Fig. 12 is an enlarged end view of the striker portion of the end casting with parts broken away;

Fig. 13 is a detail longitudinal section through the striker portion of the casting, the section being taken on the plane indicated by line 13—13 of Fig. 12;

Fig. 14 is an enlarged end elevation viewed from the right hand side of Figs. 9 and 10.

Referring in detail to the drawings, the frame consists of three main component parts comprising the end casting units A and B which are 20 spaced apart by the center sill unit C.

The end castings A and B are substantial duplicates of one another and they are united to laterally spaced rolled steel sections which are also substantially duplicates, these sections in 25 the case illustrated being in the form of I-beams. Extending laterally from the I-beams forming the center sill, there are a plurality of needle beams D. Secured to the outer end of these needle beams there are side sills E. These sills are 30 united to end sills F—F, the latter being supported centrally of their length by the end castings A and B.

End castings A and B are formed with integral draft sill and body bolster portions and also with 35 stub draft sill extensions formed with abutments which make an end to end engagement with the webs and flanges of the I-beams or other rolled metal sections constituting the center sill. The shape and proportion of the parts as will hereinafter more fully appear is such that the center line of draft substantially or approximately coincides with the neutral axes of the draft sill portions of the end castings and the center sill.

The end frames A and B are substantial duplicates, thus a description of one will suffice for both. As best shown in the enlarged sectional views of Figs. 9 and 10, each end casting includes a draft sill portion comprising longitudinally extending webs 10—10, top flanges 12—12 and bottom flanges 14—14. Extending transversely of the draft sill portion, there is a body bolster indicated generally at 16. This body bolster includes a transversely extending web 18 having integral top and bottom flanges 20 and 22. Near 45

the center, the bolster web 18 merges into a king pin bearing 24 which is formed integral with the enlarged center plate 26, this plate merging into the lower bolster flanges 14. The bearing 24 is 5 reinforced by inclined ribs 28.

Diagonal struts, indicated generally at 30, are provided which distribute the stresses transmitted to the draft sills by both draft and buffing forces so as to relieve the center plate and king-pin 10 bearing 24 of all shocks and to better distribute the loads.

The struts 30 include top flanges 32 which merge into the top flanges 12 and 16 of the draft sill and bolster portions, respectively. These 15 struts also include diagonal web portions 34, which merge into the webs 10 and 18 of the draft sills and bolster.

The draft sill portion of each end casting is provided with inwardly extending projections 36 20 and 38 which are adapted to serve as forward and rear stops for follower blocks of any suitable type of draft gear such as customarily employed in railway rolling stock. The webs 10 of draft sills are provided with suitable openings 40 25 for the accommodation of or to permit movement of the usual draft gear parts. Cored flanged openings 42 and 44 are also provided to lighten the structure.

At the outer end of each end frame, there is 30 provided an integral striker, indicated generally at 46 and which protrudes beyond the end of the frame as shown. This striker has a coupler opening 48 cored therein. The striker is provided with thickened portions, indicated at 50 in Fig. 12 35 and also includes a transversely extending web portion 52 which is integral with an upper flange 54. This flange is connected by a plurality of reinforcing ribs 56, which merge into an outer web portion 58 forming a part of the front wall 40 or face of the striker.

Each end casting is provided at its inner extremity with a pair of stub sills 60. These form in effect extensions of the draft sills and they are adapted to be riveted or otherwise secured 45 to the rolled metal I-beams 62 which constitute the center sill C. The top and bottom flanges of the beams 62 are adapted to overlap top and bottom flanges 64 formed on the stub sills. These flanges 64 are offset vertically a sufficient distance from the upper and lower surfaces of the end casting so as to form abutment shoulders 66 for the flanges of the I-beams 62. The webs of the I-beams 62 are adapted to abut vertical shoulders 68 which in effect are thickened portions of the draft sill webs 10-10. This abutting relationship of the flanges and webs of the beams 62 as illustrated in Figs. 3 and 7, provides 50 an arrangement which relieves the rivets 70, securing the I-beams to the stub sills, of shearing stresses. This is of particular importance in case of buffing forces. The abutting relationship of the parts effectively distributes such buffing forces throughout the fibre structure of the flange and web portions of the end castings. These in 55 turn transmit and distribute the forces through the diagonal braces 30. Thus, the tendency to concentrate loads is overcome and the overall strength efficiency of the structure is increased over that of structures heretofore generally used.

Preferably the line of draft, indicated by the horizontal center line X-Y of Fig. 3, substantially or approximately coincides with the neutral axis of the draft sill portions of the end frames 70 A and B as well as with the neutral axis of the

center sill C. The center sill C, as above described, comprises two longitudinally extending I-beams 62-62 which are spaced transversely. These two component parts may be considered as a single sill member whose neutral axis lies at 5 the intersection indicated at O in Fig. 5 where the vertical center line M-N between the two I-beams crosses the horizontal center line P-Q located midway between the top and bottom flanges of the I-beam 62. 10

The point O in Fig. 5 may be considered as the end projection of the center line X-Y in Fig. 3 representing the center line of draft. In an underframe as thus constructed, the metal is disposed at such locations with respect to the lines 15 along which the forces act that an excellent strength efficiency is secured. This is particularly true in the case of buffing stresses. In such stresses, the center sill can be regarded as a column in which the load is applied at one end 20 through one of the end frame castings and reacts against the other end frame casting. Such forces are effectively resisted because the draft sills and center sill of our underframe are so arranged that there is considerable metal located 25 at points quite remote from the neutral axis, thus the parts effectively resist the stresses to which they are subjected in practice.

The whole underframe is additionally stiffened and rigidified by reason of the fact that the 30 needle beams D pierce the webs of the I-beams 62-62 at the points near the neutral axis of the webs of such beams, and also because the webs are reinforced at these points by connecting brackets 72 which serve to secure the needle 35 beams to the webs of the I-beams. Moreover, the needle beams, at their outer ends, are secured to the side sills E-E which are also secured to the body bolster portions 16 of the end frames. These side sills E being connected to the 40 end sills F, which are also secured to the draft sill portions 12 of the end castings, serve to tie the parts together in such a way that the end castings A and B together with the center sill C, needle beams D and side sills E form a truss-like structure capable of counteracting draft and buffing strains and yet one which will permit of a limited amount of weaving of the underframe without damage thereto. 45

While we have above referred to the needle 50 beams as piercing the webs of the I-beams 62-62 at the points near the neutral axis of said webs, it is contemplated that in some cases each needle beam may comprise a plurality of sections which would be secured to the webs of the I-beams 55 62-62 by suitable brackets so as to avoid piercing or cutting away such webs.

While we have described quite specifically the details of the embodiment of the invention herein illustrated it is not to be construed that we are 60 limited thereto since various modifications may be made by those skilled in the art without departure from the invention as defined in the appended claims.

What we claim is:

1. An underframe for cars comprising spaced end castings each having integral longitudinal draft sills and a transverse body bolster and complementary pairs of integrally cast diagonal struts uniting said sills and bolster and rolled 70 metal center members terminating at and uniting said end castings.

2. An underframe for cars comprising end castings each having integral longitudinal draft sills and a center plate carrying a king pin bear- 75

ing, a transverse body bolster, diagonal struts whose ends unite the draft sills and bolster at spaced points said struts being adapted to relieve the center plate and bearing of draft and buffing shocks.

3. An underframe for cars comprising end castings each having integral longitudinal draft sills and a transverse body bolster and complementary pairs of integrally cast diagonal struts whose ends merge into and unite said sills and bolster and rolled metal center members uniting said end castings, each end casting having an integral reinforced striker at the outer extremity of said draft sills.

15 4. An underframe for cars comprising end castings each consisting solely of central integral longitudinal draft sills and a transverse body bolster united thereto by complementary pairs of diagonal struts, rolled metal center members having flanges and webs, said end castings having stub sills provided with seats and abutments for engagement with the flanges and webs, respectively, of said center members.

25 5. An underframe for cars including an end casting comprising draft sills having a vertical web and top flanges, a transverse body bolster having a vertical web and top flanges and complementary pairs of diagonal struts having top flanges and webs which merge into the flanges and webs of said draft sills and said bolster.

30 6. An underframe for railway cars including a one piece end frame formed with integral draft sills and body bolster, said draft sills being so shaped and positioned that their common longitudinal neutral axis and the line of draft lie substantially in the same horizontal plane.

35 7. An underframe for railway cars including a pair of one piece cast end frames each comprised solely of central draft sills and a body bolster united thereto by complementary diagonal struts and a center sill comprising a pair of rolled metal section whose ends are secured to stub sills extending inwardly from the draft sills.

40 8. An underframe for railway cars including a pair of one piece cast end frames each formed solely of draft sills and a body bolster connected by complementary diagonal struts, and a center sill comprising a pair of transversely spaced I-beams.

45 9. An underframe for railway cars including a pair of one piece cast end frames each comprised solely of central draft sills and a body bolster connected by complementary diagonal struts and a center sill comprising a pair of rolled metal sections whose ends are secured to stub sills extending inwardly from the draft sills, transverse needle beams secured to the rolled center sill sections, and rolled metal flanged side sills joint-

ly supported by said needle beams and said body bolsters.

10. A car underframe including a pair of one piece end castings comprised solely of an integral draft sill and bolster portions braced by complementary pairs of diagonal struts, a center sill including laterally spaced rolled metal sections secured in an abutting relationship to said end castings, needle beams piercing said rolled sections and connected thereto, side sills secured to 10 needle beams, and end sills connected to said side sills and said end castings.

15 11. An underframe for railway cars including a pair of substantially cross-shaped one piece cast end frames, each formed with draft sill and 15 single body bolster portions, a center sill comprising a pair of rolled metal sections, whose ends are secured to said draft sills, needle beams piercing said rolled sections and bracketed thereto, rolled metal side sills secured to said 20 needle beams and end sills secured to the side sills and to said end frames, the metal in the draft sill and the said center sill being so disposed that their respective longitudinal neutral axes coincide.

25 12. A car underframe comprising one-piece end castings each having longitudinally extending draft sill portions and body bolster portions, and a center sill secured to said castings and comprising laterally spaced rolled metal flanged 30 sections, the metal in said draft sill portions and said center sill being so disposed that the respective longitudinal neutral axis of each substantially coincides with the center line of draft.

35 13. A car underframe comprising one-piece end castings each having longitudinally extending draft sill portions and body bolster portions, and a center sill secured to said castings and comprising laterally spaced rolled metal sections, the metal in said draft sill portions and said 40 center sill being disposed substantially symmetrically about the longitudinal center line of draft.

45 14. A car underframe comprising one-piece end castings each having longitudinally extending draft sill portions and body bolster portions 45 and a center sill secured to said castings and comprising laterally spaced rolled metal I-beams whose webs are laterally spaced the same distance from a center line substantially bisecting the end castings in plan and whose top and bottom flanges are substantially equi-distant in elevation from the line of draft which substantially coincides with said center line and with the longitudinal neutral axis of said draft sill portions.
